UNITED STATES PATENT OFFICE.

CARRIE PATTON TRUESDELL, OF CLEVELAND, OHIO.

DESIGN FOR A SPOON.

SPECIFICATION forming part of Design No. 22,364, dated April 25, 1893.

Application filed February 23, 1893. Serial No. 463,491. Term of patent 14 years.

To all whom it may concern:

Be it known that I, CARRIE PATTON TRUESDELL, a citizen of the United States, residing at Cleveland, in the county of Cuyahoga and State of Ohio, have invented and produced a new and original Design for Spoons, of which the following is a specification, reference being had to the accompanying drawing, forming a part thereof.

In the drawing the upper surface or face only, of the spoon, is shown since the back is a plain surface similar in contour to that of the face.

The leading features of my design consist of a Maltese-cross, at the top of the handle, having a passion-cross in the center, within a ring; a semi-disk and a series of overlapping disks, below said Maltese-cross, forming with lily leaves and flowers the larger portion of the handle; and an engraving, in the bowl, of what was known, in Cleveland, as the Central Methodist Episcopal Church said church being the birth place of the Epworth League. The Maltese-cross A has the central ring B within which is the passion-cross C. The lines A' radiate from the periphery of the ring B to the outer edges of the cross A. At the junction of the arms which form the cross C is a halo composed of radial lines. The design above described constitutes what is commonly

known as the Epworth League insignia. The semi-disk F, depends from the lower arm of the cross A and overlaps the upper part of the disk G. Each of the disks G, H, I and J overlaps the upper portion of the disk below and 35 the disk K laps onto the handle M. Springing from the edges of the handle M and ascending both sides of the above described disks are the lily leaves N, N with the flower O on the handle M, below the disk K, and the 40 flowers O', O' each side of the disk G. The upper ends of the leaves N, N pass behind the lower angles of the lateral arms, of the cross A, and terminate against the lower arm of said cross. The arrangement of the leaves N, 45 N is substantially that shown in the drawing. Between the lower terminal of the handle M and the upper part of the bowl P is the scroll Q.

The church R is engraved in the bowl P, of 50 the spoon.

What I claim is—

The design for a spoon as herein shown and described.

In testimony whereof I affix my signature in 55 presence of two witnesses.

CARRIE PATTON TRUESDELL.
